UNITED STATES PATENT OFFICE.

JOHN ERICSON, OF SABINE PASS, LOUISIANA.

FLOATING OIL-DISTRIBUTER FOR VESSELS.

SPECIFICATION forming part of Letters Patent No. 380,479, dated April 3, 1888.

Application filed July 19, 1887. Serial No. 244,733. (No model.)

To all whom it may concern:

Be it known that I, JOHN ERICSON, of Sabine Pass, in the parish of Cameron and State of Louisiana, have invented a new and Improved Floating Oil-Distributer for Vessels, of which the following is a full, clear, and exact description.

My invention relates to a floating oil-distributer for vessels, and has for its object, when secured upon the weather side of a vessel, to automatically, by the action of the waves, distribute oil upon the troubled waters to calm the same.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a side elevation of the device, and Fig. 2 is a plan view of the same. Fig. 3 is a central vertical longitudinal section, and Fig.

4 is a transverse vertical section thereof.

In carrying out the invention a boat, A, is provided of suitable size to be carried aboard a larger vessel, provided fore and aft with transverse bulk-heads A' and a roof or cover, B.

Longitudinally and centrally the boat a shaft, B', is journaled to the under side of the cover, which shaft, extending through at the stem and stern, is provided outside the boat with downwardly-extending metal plates D. In

each end chamber, D' and D', formed by the bulk-heads, a pump, E, is vertically held, the upper end of each pump connecting with an aperture, e, in the cover, as shown in Fig. 3, the piston of the said pumps being attached to

and operated from a crank-arm on the shaft B'. The lower ends of said pumps are made to project through the bulk-heads into the larger central chamber, D', where a transverse slot is cut from the upper side of the pipe

nearly through the same. In said slots a segmental plate, F, provided with apertures f near each end, is held to slide by central attachment to a vertical rod, f', given motion from the shaft B', to which it is secured. A

counterpoise-weight, f'', is fastened to the shaft B', near each end, within the boat, whereby when the said boat is still in the water the

blades D will be kept vertical and neither aperture f in the plates F will register with the opening in the pump.

Above the apertures e in the upper surface of the cover a recess, G, is made, filled with any absorbent material, g—such as oakum—which material is held in place by a wire-netting, g'. Centrally the cover an air-pump, H, is located, adapted to be operated from the outside and purposed to force air into the compartment D'. 55

At one side of the hull a pocket, H', is produced by attaching a large piece of canvas or similar material longitudinally to the hull at the top, and also attaching the lower corners of said canvas near the bottom, the lower longitudinal edges and the ends being preferably left unattached, as shown in Fig. 4. The bottom of the hull is made slightly rounding. 60

In operation the center compartment, D', is partially filled with oil and the space intervening the surface of the oil and the top of the cover is filled with air forced therein through the pump H. 70

In the event of a storm the small oil-boat is advantageously secured near the vessel to be protected by a length of rope or in any approved manner with the pocket H' to the windward. The action of the water upon the blades D will cause the shaft B' to partially turn, which shaft will in turn cause one aperture f in the plates F to register with the opening in the oil-pumps E, and the pistons of said pumps being operated simultaneously with the inflow of oil, the said oil will be carried up in contact with the packing g, from whence, as the boat rolls, the said oil will be distributed upon the water and calm the same. The pocket H', being to windward, will be acted upon by the waves and serve to keep the oil-boat away from the vessel. The boat is provided with a trawler, S, upon the lee side, attached at stem and stern, as shown in Figs. 2 and 4, and a thimble, S', is made to slide upon said trawler, to which the rope leading to the vessel is secured, whereby the position of the boat may be accommodated to the position of the vessel when sailing before the wind. 85

Having thus described my invention, what I claim as new, and desire to secure by Letters Patent, is—

1. In a boat for distributing oil upon the

water, the combination, with the hull A, provided with a cover, B, and divided into three compartments, D', D', and D'', and oil-pumps E, located in the compartments D' and projecting into the oil-compartment D'', of the crank-shaft B', provided with external blades, D, a packing of absorbent material in said cover connected with the pump, and means for introducing air into the compartment D'', to and for regulating and supplying the oil to said packing, substantially as herein set forth.

2. In a boat for distributing oil upon the water, the combination, with the hull A, provided with a cover, B, and divided into three compartments, D', D', and D'', and oil-pumps E, located in the compartments D' and projecting into the oil-compartment D'', of the crank-shaft B', provided with external blades, D, a packing of absorbent material in said

cover connected with the pumps, the apertured swinging plates F, connected to the crank-shaft B', adapted to control the supply of oil to said pumps, an air-pump, H, located in said cover, and means for operating the oil-pumps from the crank-shaft, and means for keeping said hull to windward, substantially as shown and described.

3. The combination, with the hull A, of a crank-shaft journaled in and extending beyond said hull, blades attached to said shaft on the outside of the hull, oil-pumps in said hull and connected with said shaft, and a piece of flexible material secured to one side of said hull to form a pocket, substantially as set forth.

JOHN ERICSON.
